UNITED STATES PATENT OFFICE.

THOMAS STROUD HOSFORD, OF HIGHFIELD, COUNTY OF SURREY, ENGLAND.

BOAT-LOWERING APPARATUS.

SPECIFICATION forming part of Letters Patent No. 426,449, dated April 29, 1890.

Application filed February 21, 1890. Serial No. 341,368. (No model.)

To all whom it may concern:

Be it known that I, THOMAS STROUD Hos-
FORD, a subject of the Queen of Great Britain,
residing at Highfield, Tulse Hill, in the county
5 of Surrey, England, have invented certain
new and useful Improvements in Boat-Low-
ering Apparatus, of which the following is a
specification.

This invention has for its object improve-
ments in boat-lowering apparatus.

At the present time it is usual to lower
ship's boats from davits by means of tackles
or falls connected with the boat at two points,
one near the bow and the other near the stern
5 of the boat. This arrangement, however, is
not satisfactory and accidents occur in lower-
ing boats into the water in consequence of
the tackles or falls becoming jammed in low-
ering or one being disengaged while the other
is set or held fast, or one tackle being payed
out more rapidly than the other. I avoid
these dangers by suspending the boat while
lowering from one point only and that above
5 the center of gravity of the boat, so that she
takes the water on even keel. This I do by
means of gear which prevents undue strain
upon the boat and which automatically re-
leases the boat as soon as she rises upon the
water, or, in cases where it is preferred, the
boat may be released by hand.

In order that my said invention may be
fully understood and readily carried into ef-
fect, I will proceed to describe the drawing
hereto annexed.

5 The drawing shows a longitudinal section
of a boat fitted with lowering-gear in accord-
ance with my invention.

a a are two hooks, or it may be two **U**-form
eyes jointed at the ends at the bow and stern
of the boat, respectively. The joints
are very securely connected with the keel of
the boat by upright bolts *b b*.

c is a stanchion passing through the center
thwart and entering a socket at the bottom
5 of the boat. This stanchion can be readily
unshipped. This is the whole of the lower-
ing-gear, which remains with the boat when
afloat.

d is a beam suspended from the davits. In
order that the beam *d* may be as light as pos-
sible consistently with sufficient strength, I

prefer that it should be of steel and tubular.
The beam has slots *d' d'* at its ends which en-
gage with the hooks *a a*.

d² d² are chains upon the beam, which pass 55
to a ring *d³*, placed as nearly as may be over
the center of gravity of the suspended boat
when on an even keel; but no great accuracy
is required in this adjustment, as the trim
can be adjusted by arranging the load in the 6c
boat.

d⁴ is a ring fixed on the beam, and passing
over the stanchion *c*. It serves to keep the gear
steady. The boat may be lowered from davits
by the ordinary means, either one fall or both 65
being used and shackled to the ring *d³*. It
is then immaterial whether if both falls be
used they be eased out at the same rate or if
one be let go before the other, for then the
boat only draws a little ahead or astern and 70
does not fall off until she is floated. As soon,
however, as the water removes all strain from
the lowering-gear, the beam *d* drops out of
the hooks *a a* and the boat is released. The
hooks *a a*, as soon as they are free, fall down 75
out of the way. Both ends of the beam es-
cape simultaneously from the hooks; but
even if this should not be so no harm can re-
sult. Simply the beam will be tilted and the
hooks become free. 80

While the boat is suspended she may, if
necessary, be controlled by bow and stern lines
tended by hands on board the ship. This,
however, will only be needed in rough weather.

The boat may be lifted to the davits when 85
no longer required afloat by shipping the
hooks into the slots, and in rough weather
putting a mousing on the hooks, which is to
be removed on the boat being secured to the
davits. She is then ready for lowering again. 90

If automatic liberation of the boat when
afloat be not required, a disengaging-hook
may be substituted for the ring *d³*, and it may
be thrown off by a man in the boat as soon
as the tackles become slack in consequence 95
of the boat being floated. The chains *d²* in
this case may either pass to a beam *d*, as
shown, or the beam may be dispensed with,
the chains then passing to eyes fixed in the
stanchions in the boat. 100

What I claim is—

1. The combination, in boat-lowering gear,

of hooks a upon the boat, a beam d , hooks d' d' at the ends of the beam, engaging with the hooks a , and a ring d^3 , connected with the beam over the center of gravity of the boat and receiving the tackle or tackles by which the boat is lowered.

2. The combination, in a boat-lowering gear, of a ring d^3 over the center of gravity of the boat and receiving the tackle or tackles by which the boat is lowered, and chains d^2 d^2

above the keel and passing from the ring d^3 to points of attachment, near the bow and stern of the boat, and liberating-gear for casting off the tackles when the boat is floated.

THOMAS STROUD HOSFORD.
